UNITED STATES PATENT OFFICE

171,476

SHOE HEEL PROTECTOR

Clarice Chris Alberts, Los Angeles, Calif.

Application July 3, 1953, Serial No. 25,781

Term of patent 7 years

(Cl. D7—5)

To all whom it may concern:

Be it known that I, Clarice Chris Alberts, a citizen of the United States, residing at Los Angeles, in the county of Los Angeles and State of California, have invented a new, original, and ornamental Design for a Shoe Heel Protector, of which the following is a specification, reference being had to the accompanying drawing forming a part thereof:

I claim:

The ornamental design for a shoe heel protector, as shown.

CLARICE CHRIS ALBERTS.
